JULIUS W. GERHARD, OF ST. LOUIS, MISSOURI, ASSIGNOR TO SOUTHERN ACID AND SULPHUR COMPANY, INC., OF ST. LOUIS, MISSOURI, A CORPORATION OF VIRGINIA

PUMP

Application filed March 23, 1929. Serial No. 349,318.

My invention relates to pumps and particularly to pumps of the kind intended for impelling acids or corrosive liquids. The principal object of the invention is to produce 5 a pump of this kind that will make an efficient use of the driving power, in which the element of wear and tear will be kept as low as practicable. The invention consists in the pump hereinafter described and claimed.

10 In the accompanying drawing which forms part of this specification, and wherein like reference numerals refer to like parts wherever they occur,

Fig. 1 is a vertical sectional view of a pump 15 embodying my invention;

Fig. 2 is an elevation of the pump with the enclosing shell removed and looking at right angles to the plane of Fig. 1;

Fig. 3 is a vertical sectional view of the 20 main antifriction bearing of the pump;

Fig. 4 is a similar sectional view of the uppermost antifriction bearing of said pump; and

Fig. 5 is a horizontal sectional view on the 25 line 5—5 of Fig. 2.

In the manufacture of sulphuric acid, hot acid solution accumulates in the acid pot or tank to the depth of several feet; and from this tank the hot solution is circulated by the 30 pump through a pipe system back to the acid pot. On account of the heat and corrosiveness of the acid, the pumps heretofore used have been subject to rapid wear and tear and have required so much repair and replacement of parts that the cost of maintaining 35 them, including the loss of time while they are out of commission, has been very considerable.

According to the present invention, the 40 pump is made with a vertical casing A open at its top and at its bottom and provided about midway between top and bottom with an inlet opening 1. At all of these openings, top, bottom and side, are provided circumferential flanges that are perforated for bolts by which the adjacent parts may be secured thereto. On the exterior of the casing A near the top thereof is a perforated bracket 2 by which said casing may be secured in position. 45

50 Suspended from the top of the casing A is

the barrel of the pump which extends entirely through said casing. The upper portion of the barrel comprises a skeleton cage B in the form of a lower ring 3 that rests upon and is bolted to the top flange of said casing A, and an upper ring 4 which is connected to the lower ring by a series of vertical bars 5 preferably formed integral with them and spaced far enough apart to permit access to the interior of said cage. Said barrel also comprises an upper hollow cylindrical portion C, 55 preferably integral with the top cage B but of less diameter than the casing A and extending downwardly in the casing beyond the side opening 1 therein. Opposite said side opening 1, the hollow cylindrical portion C of said barrel has a large opening 6 in its side for the admission of liquid to the interior thereof, and there is a vertical rib 7 on the interior of said barrel extending from a point 60 some distance above said opening to a point some distance below it.

The portion of the barrel below said side opening 6 in the hollow cylindrical portion C is reduced in diameter, as at 8, and screw-threaded on the exterior of said reduced portion; and upon said reduced portion 8 is threaded an extension D of the barrel, which extension is likewise reduced, as at 9, and threaded at its lower end and upon its reduced end is a similar extension E. That is, the lower end of the body of the hollow cylindrical portion C of the barrel is reduced in diameter, and the lower end of each of the extensions D and E, respectively, is likewise reduced in diameter. 85

On top of the cage B if the pump barrel is mounted a hollow housing or shell F for the driving shaft 10 which is suitably connected to a motor or engine (not shown). 90 The lower end of said housing F has a circumferential rib or flange 11 that rests on top of the upper ring 4 of the cage B of the barrel and is secured thereto by bolts or cap screws 12. Said housing F has an annular rib 13 formed on its inner wall near the bottom to form an annular seat for the outer raceway member 14 of a ball bearing adapted for cooperation with a series of balls 15. This outer raceway member is positioned by 100

means of a plate 16 that is secured to the lower end of the housing F by means of cap screws 17 and is provided with an annular rib 16^a that enters said housing and bears against said raceway member. Said outer raceway member 14 is in the form of a ring with a thrust rib 18 at its upper end. The inner bearing member 19 is in the form of a ring with a thrust rib 20 at its lower end. 10 The inner raceway member 19 fits on a sleeve 21 whose lower end is provided with a circumferential rib 22 on the exterior thereof, which sleeve forms an angular seat for said inner raceway member. The upper portion 15 of said sleeve is of reduced outside diameter and provided on the exterior thereof with a screwthread, which is engaged by the screwthread of an adjusting ring 23 whose end bears against the top of said inner raceway 20 member. The sleeve 21 fits over a sleeve 24 whose lower end has threaded engagement with a hole in a plate 16 that is secured to the bottom of the housing.

The propeller shaft 10 extends vertically 25 through said housing F and the two sleeves 21 and 24 therein and the plate at the bottom of said housing and has its lower end formed for coupling with the propeller shaft 25 of the pump. Near its top, the housing F has 30 a rib 26 inside thereof upon which rests a perforated closure plate 27. Still nearer the top, said casing has a second offset forming a shoulder or seat for the outer raceway member 28 of an upper bearing, adapted for 35 operation with two series of balls 29. The inner raceway member 30 is mounted on a sleeve member 31 that is secured to the shaft 10; and the upper end of the housing F is closed by means of an end plate 32 secured 40 to the top of the housing by means of cap screws 33. The annular space between the upper end portion of the pump shaft 25 and the pump barrel is closed by means of a sealing ring 25^a which is supported in the opening 45 in the bottom of the skeleton cage B of said pump barrel.

The pump shaft 25 is located axially in the barrel of the pump, with its upper end coupled endwise to the propeller shaft 10 by 50 a suitable coupling located opposite the openings in the cage B. In the construction illustrated, the pump shaft 25 is preferably a hollow cone with its large diameter at the top where it is provided with an exterior circumferential rib 34 that is perforated to receive locking bolts 35 that pass through a similar flange 36 at the bottom of the propeller shaft 10. The pump shaft 25 is supported wholly 55 by the propeller shaft 10 and extends entirely 60 through the pump barrel. The lower end of the main body member C of the pump barrel has a spider 37, preferably formed integral therewith with an axial opening there-through which is provided with a bushing or 65 bearing member 38 that serves as a guide

and bearing for the pump shaft. Likewise the bottom member E of the pump barrel has a spider 39 therein which has an axial bore in which is mounted a bushing 40 that serves as a guide and bearing for the lower end 70 portion of the pump shaft 25. The lower end of the intermediate member D of the barrel is likewise preferably provided with spider 41 and guide bore for the shaft 25. Suitable impellers G are mounted on the pump shaft. 75 In the construction shown, one impeller is mounted below the uppermost spider 37 and above the middle spider 41 and the other impeller is mounted on the shaft below said middle spider and above the lower spider 80 39. During pumping, the upward thrust on the pump shaft is resisted by the thrust bearing 15. The spider 37 has radial vanes which serve to guide the liquid against the uppermost impeller; and the spiders 40 and 41 have radial or helical vanes which operate to convert the rotary or centrifugal motion given to the liquid by the impellers into an axial direction of flow. The number of impellers are in proportion to the lift desired. 85

A suitable type of impeller comprises a central hub 43 with helical vanes 44 that fit freely in the respective portions of the pump barrel in which they are mounted, said vanes being of the proper lead to impel liquid 90 downwardly. The impellers are fixed to the pump or propeller shaft preferably by means of split hollow cone wedges 43^a that are forced into the impeller hubs by nuts 43^b threaded on the lower ends of said cone 95 wedges.

The bottom of the pump casing A is secured to a hollow reducing member I whose upper diameter is substantially the same as that of the pump casing and whose lower diameter is reduced to correspond with that of the pipe system connected therewith. In the construction illustrated, the reducing member I has circumferential ribs or flanges at top and bottom perforated to accommodate bolts that extend through similar ribs at the bottom of the barrel casing and at the top of a quarter turn fitting J. This last mentioned fitting is equipped with a pedestal 45 that is preferably integral therewith and serves as the 105 main support of the pump. 110

Between the lower end of the pump casing A and the top of the reducing member I is clamped a ring 46 that fits around the lowermost shoulder portion of the extension E of the barrel casing and serves to close the annular space between the barrel of the pump and its casing. 115

The operation of the construction herein-before described is as follows: The weight of the pump is supported by the pedestal 45 and the pump is steadied in its vertical position by the bracket 2 at the side thereof. The drive shaft 10, which is suitably connected to an electrical motor or other source of power, 120

is driven in such direction that the impeller blades G force the liquid downwardly. As the pump shaft 25 is hung from the propeller shaft, the entire weight of the moving parts is supported by the ball bearings on which the propeller shaft is mounted. Assuming that the inlet port 1 in the side of the pump casing A is in communication with the acid pot or tank and the elbow or fitting J at the bottom of the pump casing communicates with said acid tank, the acid entering said inlet opening is propelled downwardly by the impeller vanes and out through the bottom of the casing whence it is forced back to the acid pot or to such other point of delivery as may be desired. As the impeller vanes are arranged to drive the liquid downwardly, the reaction tends to lift the pump shaft 25 and the driving shaft 10 from which it is suspended, and such tendency results in an easing of the thrust on the ball bearings which support said shafts. It follows, therefore, that the greatest end thrust on said bearings is the downward thrust due to the dead weight of the pump shaft and parts mounted thereon, when said shaft is stationary. When the shaft is in motion, the reaction of the impeller vanes against the liquid tends to offset said dead weight and appreciably reduce the downward thrust on said bearings. In fact, under certain conditions, the initial downward thrust on said bearings is reversed and the end thrust on the bearings is in an upward direction.

It is noted that on account of the initial end thrust on the supporting bearings being eased or reversed in operation, the wear on said bearings is considerably reduced and the life thereof is greatly lengthened. It is also noted that on account of the acid being forced downwardly and delivered through the bottom of the casing, the danger of leakage at the top of the casing is minimized or eliminated and the usual stuffing box is dispensed with. It is further noted that by reason of the sealing ring 46 at the bottom of the casing A all of the liquid is forced to pass through the barrel of the pump and is delivered in such manner that it cannot return.

It is obviously a great advantage of my construction that the pump shaft and the pump barrel can easily be removed from the pump casing without disturbing the pipe connections of said casing and without disturbing the devices that fasten it in place. It is also noted that the bearings of the shaft are located where they are entirely free from contact with the liquids.

While my invention is particularly valuable for pumping hot acid solution in the manufacture of sulphuric acid, it is obviously applicable to other uses.

What I claim is:

1. A pump comprising a casing having an inlet opening in the side thereof and a de-

livery opening in the bottom thereof, a barrel suspended from the top of said casing having an inlet opening opposite the inlet opening of said casing and an outlet opening at the bottom thereof, and a shaft suspended inside of said barrel having impellers thereon adapted to force the liquid downwardly, said barrel having a vertical rib on the interior thereof extending across said opening opposite said shaft, said shaft being supported above said inlet openings by antifriction bearings adapted to take care of vertical thrust and radial load, and below said inlet openings by bearings provided therefor in said barrel.

2. A pump comprising a casing having an inlet opening in the side thereof and a delivery opening in the bottom thereof, a barrel suspended from the top of said casing and having an inlet opening opposite the inlet opening of said casing and an outlet opening at the bottom thereof, a propeller shaft suspended inside of said barrel above the inlet opening thereon, said shaft being supported by antifriction bearings adapted to take care of vertical thrust and radial load, a pump shaft suspended inside of said barrel from the lower end of said propeller shaft and having impellers thereon adapted to force the liquid downwardly, means for closing the annular space between the upper end portion of said pump shaft and said barrel, said barrel being provided below the inlet opening thereon with bearings for supporting the lower end portion of said pump shaft.

3. A pump comprising a casing having an inlet opening and a delivery opening located below said inlet opening, a barrel suspended inside of said casing from the top thereof, said barrel being provided opposite the inlet opening of said casing with an inlet opening and being provided adjacent to the discharge opening of said casing with a discharge opening, a shaft located inside of said barrel and having impellers thereon adapted to force the liquid downwardly, and radial and end thrust bearings mounted on the upper end of said barrel for supporting said shaft therein, said casing being provided in its top with a laterally extending bracket and at its bottom with a supporting pedestal.

4. A pump comprising a casing having an inlet opening in the side thereof and a delivery opening in the bottom thereof, a barrel suspended from the top of said casing and having an inlet opening opposite the inlet opening of said casing and an outlet opening at the bottom thereof, means for closing the annular space between said casing and said barrel at the lower end of the latter, a shaft suspended inside of said barrel and having impellers thereon adapted to force the liquid downwardly, means for closing the annular space between said shaft and said barrel at

the upper end of the latter, and antifriction bearings mounted in said barrel above the means for closing the space between said shaft and the upper end of said barrel and adapted to take care of vertical thrust and 5 radial load.

5. A pump comprising a casing having an inlet opening in the side thereof and a delivery opening in the bottom thereof, a barrel suspended from the top of said casing and having an inlet opening opposite the inlet opening of said casing and an outlet opening at the bottom thereof, means for closing the annular space between said casing and said barrel at the lower end of the latter, a shaft 10 suspended inside of said barrel and having impellers thereon adapted to force the liquid downwardly, means for closing the annular space between said shaft and said barrel at 15 the upper end of the latter, and antifriction bearings mounted in said barrel above the means for closing the space between said shaft and the upper end of said barrel and adapted to take care of vertical thrust and 20 radial load, said barrel comprising a main body portion having an extension threaded thereon below the inlet opening therein and a similar extension threaded on the lower end of said first mentioned extension, the 25 lower ends of said main body portion and said extensions being provided with bearings 30 for the lower end of said shaft.

Signed at St. Louis, Missouri, this 21 day
of March 1929.
